POWER DIPPER CONSTRUCTION**Edward J. Charlton, Coatesville, and Leonard Pompa,
Philadelphia, Pa.****Application July 29, 1950, Serial No. 176,656****7 Claims. (Cl. 214—145)**

This invention relates to power dipper construction and particularly to dippers of exceptional size and strength, for use on very large material-handling machines, such, for example, as are employed in the strip mining of coal. In that field of operation, it is customary to use large power shovels, operated by electric motors or diesel engines, in stripping away the surface layers of earth in order to lay bare the underlying layers of coal. This involves moving large quantities of earth for short distances, and for this purpose, shovels of large cubic yardage are desirable, and heretofore it has been the practice to use shovels of 7-yard, 12-yard, and even 20- or 30-yard capacity; although the larger of these machines have been subject to frequent failure of one part or another of the dipper structure, owing to the immense forces set up during the digging and lifting operations.

While various features of the present invention are doubtless advantageous in dippers of smaller sizes, it is a major purpose of the present invention to provide an exceptionally strong and rugged dipper construction, of a minimum weight for its capacity and strength, especially useful in immense dipper sizes, such as 40 or 50 cubic yard capacity, or even larger—adapted for use in the particular service hereinabove described.

In carrying this general object into effect, we have also kept in view a number of other objects, among which we will briefly mention several. For example: It is an object of the invention to improve and render less expensive the manufacture of large-size dippers, by providing an unusual design of dipper which is especially adapted for construction from high-strength rolled steel plate, so chosen, formed, and arranged in the dipper structure, that the assembly may be largely if not entirely welded, by desirable and established welding procedures, into a unified, rigid, integral whole. It is a further object to provide such a dipper of such form that the necessary strength of the various parts of the dipper and of the dipper as a whole may be secured from plate material involving the least possible complication of bending or other forming—utilizing, wherever feasible, standard and/or very simple forms of flat, bent, curved, and channeled pieces. It is a further object to so form and position these pieces that a minimum of material (as to weight) is utilized in securing a maximum of strength, and that the welded joints employed in assembling and unifying the various pieces are of such joint types and are so located that they will be least subject to fatigue and other failures.

Still further, the invention contemplates the securing of the foregoing objects by or in a construction wherein lightening apertures are used for other purposes, such as for access to internal welds and for access to operating parts housed within the structure. Further in this regard, the invention contemplates the formation of certain hollow structural assemblies or sub-assemblies in such manner as to serve advantageously for housing, positioning, guiding and protecting various working parts of the dipper mechanism.

2

In regard to the preferred form of assembly and securing of the parts constituting the dipper, which is for the most part of welded construction, the invention also contemplates the disposition of pivot assemblies for the dipper and bail, and also the construction and location of the mountings therefor, and the disposition and configuration of the bracing structures (especially of certain triangulated braces), in such manner that all these parts cooperate to secure the maximum strength with the minimum weight, and to gain the greatest advantage in the way of protection of the working parts of the mechanism.

In carrying out all of the foregoing, the invention further involves the use of a minimum of forged and other specially configured parts, the elimination of most if not all of the riveting frequently found in dippers, and the formation and assembling, of such special parts as are employed, in such manner that they may be welded into the assembly or various sub-assemblies of the dipper at points where the welds will be least likely to be ruptured in service and also where they may be easily machined and readily inspected; and in this regard also the construction makes possible the use of easy lines of curvature of the structural parts, between or adjacent to welded connections.

How the foregoing, together with such other objects as are incident to our invention, may be secured will be evident to those skilled in the art, from the following description, taken together with the accompanying drawings, wherein:

30 Figure 1 is an elevational view of the left side of a power dipper, omitting most of the dipper handle and bail, with portions broken away and others shown in section; the front portion of the dipper bucket being at the bottom of this figure, as though the bucket were resting on the ground in position to dig into a mass of material.

35 Figure 2 is a view of the dipper, partly in section, taken on the line 2—2 of Figure 1.

Figure 3 is a view taken on the section line 3—3 of Figure 1, showing the digging teeth in relation to the lip of the bucket.

40 Figure 4 is an end-on view of the lip and tooth arrangement of Figure 3.

Figure 5 is a section taken through the front portion of the bucket on the line 5—5 of Figure 1.

45 Figure 6 is a section through the front portion of the bucket, near the bottom thereof, taken on the line 6—6 of Figure 1.

Figure 7 is an outside view of the digging wall of the bucket omitting the teeth at the digging edge, and omitting the dipper door.

50 By reference first to Figures 1 and 2 it will be observed that the power dipper of the present invention comprises, in a broad way, a bucket generally designated B, a handle (shown in part) generally designated H, an intermediate portion generally designated I, a dipper door generally designated D, and a lifting bail (shown in part) generally designated L.

55 As is clear from the drawings, the bucket portion B constitutes hollow box-like structure, and in the preferred embodiment of the invention it is composed almost entirely of high-strength rolled steel plate elements welded together in a new and especially advantageous relationship. Similarly, the intermediate section I (which forms the attachment for the handle and is in turn secured to the back edges of the bucket and has front wall construction which serves also as the back wall construction of the bucket) is a hollow box-like structure of steel plate welded together. Novel and advantageous features are also involved in the hollow box-like bracing structures at the front of the bucket portion B.

60 65 70 75 The bucket B, which is of the digging scoop type, is entirely open at the top and has its bottom closed by the

door D, as is usual in the art. The side walls of the bucket are formed largely of very heavy outside plates of rolled steel, which also serve as a reinforcing frame, and inside plates of lighter gauge, which close off the openings cut in the outside plates, each such outside wall member (in the present instance) being formed of two plate members 25 and 25' which are welded together along the line 25W. In this instance the bucket is so large (the 50 cubic yard size here depicted for illustration, having inside cross-sectional dimensions of approximately 10 to 12 feet, and being capable of having a good-sized automobile truck driven right through it—when in the position of Figure 2) as to require separate plates 25 and 25', in view of the fact that a single plate of the required size is not available from rolling mills generally.

These plates, in the construction depicted, are about 3 inches thick and serve both as an enclosing and a lifting frame for the bucket. Together they are formed, as by flame-cutting, to provide the lightening apertures 25a; the remaining plate frame comprising what may be termed generally parallel back and front members 25b, 25f, upper and lower members converging from front to back 25u, 25l, and intersecting diagonal bracing members 25x, 25x'. It will be noted that one of these diagonal braces runs in a direction generally from the location of the digging teeth 26 at the lip of the bucket toward the back bottom corner of the bucket, and the other runs generally from the location of the bail pivot 27 to the lower front corner of the bucket; the back and front portions of the bucket being respectively associated with the hinge and latch assemblies for the door, as will later be described.

An internal lining or wall member 28 (typically, in this example, of 1 inch rolled plate) will be seen from Figures 1 and 2 as being welded in place just inside the main side plate members just described. The internal side plate members 28 extend downwardly below the outside frame structure 25l, as shown at 28e, to form side wall extensions, whose extreme bottom edges are closely parallel to the plane of the main top plate of the door D. At the back of the bucket there are diagonal corner plates 28c and back plate 28b, which complete the inside defining walls of the rear portion of the bucket. As will later be brought out, the latter walls cooperate with or form part of the intermediate structure of the dipper hereinafter to be described.

The front portion of the bucket B (as seen in Figures 1 to 7 inclusive) comprises a transversely curved main plate 29 (typically of 1 inch or 1½ inch stock) which at the bottom is reinforced by a heavy outside plate member 30 extending from one side to the other, at the sides is welded to the transversely curving upright front portions of the elements 25f of the outer side frame plates 25, and at the top is reinforced and completed by the extra heavy transverse lip member 31 and the two side gussets 32 which are securely welded by merging horizontal and upright welds to the main plate structure 25.

The digging lip formed of plates 31 and 32 is in this instance shaped from 3½ inch plate, and the main lip member 31 is given a slight outward inclination at its outer edge. The digging teeth 26 are securely welded to this heavy lip plate 31 at seats 33 cut thereina for the purpose. We have found by actual test that the size, strength, angle, and anchorage of this heavy lip construction (in substantially the shape and proportions herein illustrated and described) are of great, if not critical, importance in preventing failure of the dipper under the strain of the digging loads imposed.

The bucket B is further strengthened and reinforced across its front face (as seen in Figs. 1, 5, 6, and 7) by a series of transversely arched internal channel-shape plate members 34, firmly welded in position on the outside of the front wall 29, and by vertical hollow members 35, desirably of semi-cylindrical form, the latter being more numerous toward the bottom portion of the front wall of the dipper where there is greater pressure on the material

in the dipper as it is lifted, and also a heavy downward force imposed by the door latch.

The latch-bar keeper 36 may be riveted and welded at the central part of the lower edge of the front wall of the dipper, being securely fastened to the main bottom transverse bracing plate 30. As shown, this keeper is welded peripherally and also on the inside of a couple of apertures seen at 37 in Figure 6. The keeper has an opening 38 to fit the latch-bar of the dipper door D.

For cooperation with the dipper door D, and for strengthening the bucket at the point where the door must abut the bottom of the bucket, external flanges 25z are provided at the front portion of the lower front edges of the bucket.

For cooperation with the dipper lifting bail, each member 25' has an upwardly extending ear 39 (Fig. 1), which on each side is reinforced by additional plate members 40, welded in position, this assembly being bored to provide a support for the bearing sleeve 41 (Fig. 2) engaging the pivot 27 which in turn cooperates with the lifting bail L. In this region, the side walls of the dipper are further reinforced by flanging 42 on the outside and 43 on the inside of the bucket. This flanging extends rearwardly and merges (as seen in Fig. 2) with the upright wall structures of the intermediate portion of the dipper, the inner flanging 43 merging with the back corner wall plates 28c of the bucket, and the outside flanging 42 extending back to about where the outside wall plates 44 are secured to the main side wall structure 25'. From about the plane of the rear wall 28b of the bucket, the outside walls 45 extend rearwardly in rather sharp convergence to the zone of attachment with the dipper handle proper. Similarly the upper and lower plates 46 and 47 converge rearwardly in a continuation of the converging slope of the upper and lower edges of the side walls of the bucket.

In general it may be said that an approximately perimetral boundary of the forward part of the structure 45, 45, 46, and 47 is secured to the side and rear wall structures of the bucket (all by welded joints); or alternatively this whole structure may be deemed a part of the bucket proper, or the wall structure 28b, 28c may be deemed a part of the intermediate structure. In any event, the internal wall structure 28b, 28c effectively constitutes the back inside wall of the bucket, and rearward thereof the structure forms a box-like housing for the dipper shock absorbing mechanism 48 seen partly in full lines and partly in dotted lines in Figure 1. This mechanism (with which the present invention is not specifically concerned) is mounted by a bracket 49 on the rear wall 28b of the bucket, and it has an operating rod 50 which cooperates with the dipper door. Access and lightening apertures 51, 52, and 53 are provided in the structure in positions where a minimum of weakening effect results and where accessibility to internal welds and to the shock absorbing mechanism is required. Light-weight cover plates 54 may be applied over any of these apertures (as shown in Fig. 2). Apertured inside bracing bulkheads 55, 56, and 57 are also provided at the important locations shown.

The bottom wall 47 (which is heavily reinforced and heavily braced, as shown) carries, at a location between the bucket wall 28b and the bracing bulkhead 57, heavy bearing brackets 58 (Fig. 1) for the hinge 59 of the door D.

Thus the structure I serves not only as an intermediate joining portion between the bucket portion and the handle portion of the dipper, but also as an important foundation structure for the mounting parts both inside and outside.

The wall 46 abuts the top wall 60 of the dipper handle structure, and an angular extension 47' of the wall 47 abuts the angular extension 61' of the bottom wall 61 of the dipper handle. Side walls 62 and internal transverse brace 63 complete this portion of the handle, which

is welded at 64 to the intermediate structure I. An external V-shaped structure brace 65 completes the junction of the parts at this region. The side plates 62 of the lower portion of the dipper handle may be flared outwardly as shown in plan in Figure 2. The V-structure 5 65 is a deflector to keep any over-load of rocks or dirt from running down the dipper handle (when lifted) and causing damage to the machine or injury to the operator; but at the same time it is so positioned as to serve as an external brace at the juncture of the dipper handle with the portion I of the dipper. The remainder of the dipper handle construction will be described after the description of the construction of the dipper door D and the lifting bail L.

The door D is shown in position on the dipper in 15 Figure 1. The door comprises a heavy inner wall 66 of steel plate (serving as a compression member when the dipper is loaded), a relatively lighter outer wall 67 of plate, which may be very largely cut away with lightening and access apertures (not shown), and intermediate 20 structure (not shown) between the walls. The door has a hinge construction and associated parts indicated by 59, and is connected with shock absorber mechanism 48. Within the door is disposed latch bar 84 (Figure 1) together with its operating mechanism generally indicated 25 at 85.

In summary, it may now be seen that we have provided by our invention a power dipper of exceptional strength and capacity for a given weight, having the capability of long life in hard service without frequent 30 failures of welds or other parts of the structure; and have accomplished this by a considerable number of coordinated features of construction, configuration and relationship which are quite novel in this art, the advantages of which will be readily recognized by those experienced 35 in this field.

We claim:

1. For a dipper of the character described, a main bucket body comprising relatively thick rolled plate side wall structural members and a dipper lip member, and 40 relatively thinner rolled plate front and back wall members, all fixedly joined in an integral construction wherein there are built-up hollow box-like reinforcing structures of relatively thin rolled plate welded to said front and rear walls exteriorly thereof, the structure welded to 45 one of said walls comprising transversely extending hollow box-like members and, between said members, vertically extending hollow strengthening members.

2. A power dipper bucket comprising: a back portion including an inner and an outer wall, intermediate bracing between said walls, the inner wall substantially defining the back load-handling surface of the bucket; a 50

front portion including an inner wall substantially defining the front load-handling surface of the bucket and grill-like bracing welded to the wall; two side wall portions each comprising a reinforcing frame generally in the form of a truncated triangle with diagonal braces substantially connecting opposite vertices and an inner wall secured to the frame substantially defining a side load handling surface of the bucket; welded joints respectively interconnecting said reinforcing frames with the inner and outer walls of said back portion; a bottom portion comprising a door having a wall substantially defining the bottom load handling surface of the bucket; welded joints interconnecting said frames and the wall of said front portion; and pivotal connections between said door and the intermediate bracing of said back portion.

3. A construction in accordance with claim 2 further including bail connections secured to each frame and disposed toward the top of the bucket and lying along one of said diagonals.

4. A construction in accordance with claim 3 wherein the inner and outer walls of the back portion extend downwardly in a converging manner toward said frames.

5. A construction in accordance with claim 2 wherein each inner wall portion of the respective side walls extends outwardly from its frame toward the bottom of the bucket, the edges thereof being adapted to mate with the wall of said door.

6. A construction in accordance with claim 2 further including a plate of thickness greater than the thickness of a frame disposed near the top of the bucket and extending between said frames, welded joints interconnecting the plate with the frames and with the inner wall of said front portion and a plurality of digging teeth set in seats in said plate and welded thereto.

7. A construction in accordance with claim 6 wherein said plate tilts outwardly toward the front of the bucket.
